UNITED STATES PATENT OFFICE.

HENRY E. BRETT, OF LOS ANGELES, CALIFORNIA, ASSIGNOR TO THE MILLS AUTOMATIC PRESS COMPANY, A CORPORATION.

AUTOMATIC PRINTING-PRESS.

No. 872,108.

Specification of Letters Patent.

Patented Nov. 26, 1907.

Application filed January 4, 1907, Serial No. 350,833. Renewed September 30, 1907. Serial No. 395,288.

To all whom it may concern:

Be it known that I, HENRY E. BRETT, a citizen of the United States, residing at Los Angeles, in the county of Los Angeles and State of California, have invented new and useful Improvements in Automatic Printing-Presses, of which the following is a specification.

My invention relates to a printing press in which the paper is automatically fed and held while the same is being printed and the sheet will then be automatically delivered out of the machine; and the object thereof is to provide an efficient, rapid acting machine for that purpose. I accomplish this object by the mechanism described herein and illustrated in the accompanying drawings, in which:

Figure 1—is a side elevation partly in section of my improved printing press. Fig. 2—is a plan of the same. Fig. 3—is a section of the upper portion of my machine on the line 3—3 of Fig. 2. Fig. 4—is a detail of a portion of the mechanism shown in Fig. 3. Fig. 5—is a section on the line 5—5 of Fig. 2. Fig. 6—is an enlarged detail of a portion of the mechanism shown in Fig. 5. Fig. 7—is a central section of the cylinder and a portion of the piston shown in Fig. 6. Fig. 8—is a section on the line 8—8 of Fig. 1. Figs. 9 to 13—are views relating to the vacuum mechanism. Figs. 14 to 19—are views relating to the paper feed mechanism.

In one side of the frame 20 of the machine is mounted the driving shaft 21, on the outer end of which is the power pulley 22 which is driven by belt 23 or in any other suitable manner. On this shaft is a fly wheel 24 of usual construction. Shaft 21 has rigidly mounted thereon a pinion 25 which meshes with gear 26. Gear 26 is mounted on crank shaft 27 which is provided with crank 28. The arms of crank 28 project on both sides of shaft 27, as shown in Fig. 8, and the unconnected ends are provided with counter-balancing weights 29 and 30. A pitman rod 31 is pivotally connected at one end to crank 28 and at the other end to arm 32, which arm is rigidly secured to the lower side of the type carrying frame 33, and as said crank is rotated said pitman causes a reciprocation of the type carrying frame on the inclined guide ways 34. As best shown in Fig. 5 the type frame has a depression or pocket 35, in which is carried a form box 36 which is vertically

movable therein so that the type 36^a (Fig. 17) which are locked in a form and placed in said box and locked therein may be raised when the frame is moved to the left to engage or contact with the paper to be printed, 60 which paper is held on cylinder 37 while it is being printed.

Movement of the form box.—The form box rests upon and is supported by shafts 38 and 38^a which are flattened as shown in Figs. 5 and 6. When the type are not intended to contact with the cylinder on the movement of type carrying frame the form box rests upon the flattened portion of the shafts as shown in Figs. 5 and 6. These shafts are 70 mounted in bearings secured to the bottom of the pocket. To these shafts are secured levers 39 and 39^a which pass through slots in the bottom of the pocket and are pivotally united to a carrying bar 40 provided 75 with a downwardly extending arm 41. In the lower end of arm 41 is a small wheel 42 which will ride on an incline formed by a trap door 43 when the frame is moved to the left, if said trap door is let down as shown in 80 Fig. 5. This trap door forms a part of the inclined side raising track 44 which is secured to a side bar forming a part of the frame. When wheel 42 travels up the incline formed by the trap door levers 39 and 85 39^a are rocked, whereby the round portions of the shafts are brought beneath the form box which raises it sufficiently to bring the type into engagement with the paper on the cylinder. This track is cut away at 45 so 90 that when the roller 42 reaches that point it will drop through the track and thereby cause the rotation of shafts 38 and 38^a to bring the flat portions thereof in contact with the form box, thereby permitting the 95 same to drop to the position shown in Fig. 5, in which position the type will not contact with cylinder 37 when the frame is moved in either direction. It will be understood that the length of track 44 from the point at 100 which the trap door is pivoted to the point where it is cut away is sufficient to keep the type in contact with the paper on cylinder 37 while said cylinder makes a complete revolution. Spring 39^b causes the quick return of 105 the levers.

Exhaust mechanism.—Within cylinder 37 is an air chamber 46 which is provided with a plurality of ports 47 which open through the top of the casing of the cham- 110

ber, which casing forms a portion of the cylinder, the same being cut away at this point. A pipe 48 connects chamber 46 with shaft 49 upon which cylinder 37 is mounted. 5 This shaft from its connection with that of pipe 48 to the outer end is hollow as shown in Fig. 3 and passes through a bearing block 50 which is mounted and movable in a guideway 51 in the top of the frame. A similar 10 block and guideway is provided at the other end of the shaft. The outer end of the shaft is closed by a plug 52. Near the outer end this shaft passes through the casing 53 of an air chamber 54, within which chamber the 15 said shaft is provided with ports 55 which connect the interior of said shaft with said air chamber. Connected to said casing and in communication with said air chamber is a pipe 56 which has a cut off valve or cock 57 thereon. Pipe 56 is connected by a flexible 20 hose 58 with pipe 59, which last pipe is provided with a T-fitting 60. Pipe 59 is connected to the casing 61 of the air controlling valve chamber 62, in which last chamber is 25 the hollow valve 63, shown in detail in Fig. 9. The outer end of this valve chamber is closed by a perforated plate 64 against which one 30 end of spring 65 bears. This spring is partly housed within valve 63 and exerts its power toward forcing said valve out of chamber 62. Valve 63 has a stem 66 which screws into the outer end thereof so that its length may be 35 regulated and a lock nut 67 secures it in its adjusted position. This stem passes through a bearing 68 which is secured or integral with an extension of the casing of the valve chamber which is secured to the frame of the machine. Key 68^a prevents it from rotating in its bearing. In the outer end of this stem is 40 a bearing wheel 69 which provides a rolling contact between said stem and cam 70, which cam is mounted upon shaft 27. Pivotally connected with cam 70 is pitman 71, the other end of which is connected to piston 72 45 which has a working fit in cylinder 73. The interior of cylinder 73 is connected by pipe 74 with the interior of the air controlling valve chamber 62. As shown in Figs. 9 and 10, on the inner side of the casing 61 of the air controlling valve chamber are channels 75 and 50 76, into which channels pipes 74 and 59 respectively open. The central portion of valve 63 is reduced in size as shown at 77 in Fig. 9 so that when the valve is in the position shown in said figure pipes 59 and 74 are 55 in communication through the valve chamber and when the valve is in the position shown in Fig. 10, the rear end thereof cuts off communication between said pipes and pipe 59 is in communication with the open air. 60 The purpose of this construction is to cause chamber 46 to have the air exhausted therefrom by the reciprocation of piston 72 in cylinder 73, the position of cam 70 on its 65 shaft being such that when piston 72 is at

about the central portion of its downward stroke, cam 70 operates valve 63 to establish communication between pipes 59 and 74. At the same time that this communication is established, the paper carrier 75^a brings the 70 sheets of paper 76^a so that one end thereof rests upon the casing of chamber 46 directly over ports 47 so that the bottom sheet is held by suction upon said ports.

Movement of paper cylinder.—At each end 75 of cylinder 37 are cog gears 77 which mesh with racks 78 on the sides of the type carrying frame 33, whereby as said frame is moved on its guideways, said cylinder is caused to revolve, first in one direction and then in the 80 other direction, depending upon the direction that said frame is at that time traveling. Shaft 49 (see Fig. 3) is provided with a pinion 79 which meshes with a rack 80, which last rack is rigidly secured to the frame of the 85 machine so that when the cylinder is rotated it causes the travel of block 50 in guideway 51 in the reverse direction to which the type carrying frame is traveling, whereby the paper on said cylinder is brought into contact 90 with the type carried by said frame, the same being elevated as before described as the frame travels to the left and depressed so as not to contact therewith when the frame travels to the right. A like pinion and rack 95 is at the other end of the shaft.

Delivery of printed paper out of machine.—The movement of the cam 70 is so timed that just as the exhaust is cut off, the sheet of paper on the cylinder is engaged by a friction 100 roller 81 mounted on shaft 82, as best shown in Fig. 18, and is kept by said roller in engagement with said cylinder. As best shown in Fig. 5 a portion of cylinder 37 is cut out at 83 and in this cut out portion is secured the 105 casing of chamber 46. In the top of the casing of chamber 46 are grooves 84, shown in Fig. 18. Secured to shaft 85 is the delivery apron 86 which is provided with fingers 87 that pass into grooves 84 as the cylinder is 110 rotated and lift the paper off the cylinder so that it will pass upon the delivery apron as the cylinder is revolved to the right. Cams 88 are mounted on shaft 49. These cams 115 are circular except adjacent to the opening in cylinder 37 where they are cut away, as shown in Fig. 18. Curved arms 89 are secured to the delivery apron and project downwardly slightly therefrom. These arms ride upon cams 88 and are held spring 120 pressed against the same by spring 90 secured to the shaft and to its bearings, and when they reach the cut away portion of the cam they drop down into the grooves and are raised up out of the grooves and above 125 the cylinder when the circular portion of the cam is again reached. The delivery apron is provided with an upwardly extending arm 86^a (see Fig. 15) which engages a lug 86^b on the side of the frame when chamber 46 is be- 130

ing exhausted so as to hold the delivery apron from dropping when the cut away portion of cam 88 is reached. As the cylinder revolves this apron causes the printed sheets to pass into the collection box 91.

Inking device.—An ink fountain 92 is secured to the type carrying frame and has a roller 93 therein which engages the inking rollers 94 as the frame is reciprocated and carries on the said inking rollers the necessary ink to ink the type as they pass under said inking rollers. Spreading rollers 95 are provided to take off the surplus ink.

Paper carrying mechanism.—The paper carrier has an adjustable back 96 so that it can be adjusted to paper of different widths and is supported by a plate 97 upon which it reciprocates. The front 98 of the paper carrier is hinged at 99 to an adjustable arm 100 which is secured to ledge 101, which ledge forms the lower part of the side of the carrier. A bolt 102 passes through the front plate and screws into the end of the ledge and is provided with a nut 103 which acts as a stop to hold the front plate in a vertical position as shown in Fig. 5. Between the head of this bolt and the front plate is a spring 104 which holds the plate yieldingly engaging said nut. It will be observed that the lower end of the front plate is engaged by the casing of chamber 46, which as it rotates will cause the lower portion of the plate to swing outwardly until it passes below the end of the plate when the same will spring back 35 against the front end of the paper in the carrier, thereby packing the same.

Movement of paper carrier.—The movement of the paper carrier is not my invention. It is effected as follows: A rod 105 is secured to the sides 106 of the paper carrier and on this rod is mounted an adjustable pitman 107, the other end of which is secured by bolt 108 to lever 109. Bolt 108 passes through lever 109 in slot 110 to adjust the travel of the carrier. Lever 109 is pivoted at 111 to a bearing 112 secured to the frame of the machine at the center of the rear end thereof. To this lever is secured an arm 113 which has a cam slot 114 therein, the front end of which projects downwardly as shown in Fig. 1. Within this slot is a roller 115 which is mounted upon bolt 116, which bolt is the pivot which unites pitman 31 with arm 32. From this construction it will be seen that the paper carrier will be moved forward whenever the roller 115 enters the forward end of the cam slot and that when it moves in the reverse direction it will be moved backward until the roller reaches the horizontal or rear portion of the cam slot when the paper carrier will have no motion. This movement is so timed that just before the extreme limit of forward movement of the paper carrier has been reached the lower 65 sheet of the paper in the carrier is brought

into contact with and rests upon the casing of chamber 46 at the time said chamber is thrown to suction. At this time the paper carrier is also moving to the right so that the lower sheet of paper is drawn away at its 70 front end from the other sheets of paper.

Mechanism for supporting the front end of the paper.—As soon as the front end of the lower sheet of paper has dropped below the other sheets a supporting rack consisting of a 75 plurality of fingers 117 is brought beneath the front end of the sheets to support them as they move still further forward until they reach their extreme motion to the right as shown in Fig. 16 when the paper carrier 80 quickly travels to the left and off said rack. These fingers are secured to bar 118 by means of set screws 119 so that they can be adjusted. Bar 118 is moved by the L-shaped lever 120, in the outer end of which is 85 a roller 121, which roller engages and rides upon track 122 secured to the side of the paper carrier so that as the paper carrier moves forward or to the right said track will engage said roller and thereby move the fingers upwardly so that they will support the front 90 ends of the sheets of paper during the latter part of their travel toward the right or forward and also on the first part of their travel to the left or backwardly. The front portion of this track slopes downwardly so 95 that the front end of the sheets of paper will be over the points of the fingers before they are raised in contact with the paper.

Mechanism for controlling the trap door.— 100 As before stated pipe 59 is provided with a T-fitting 60 and to this fitting is connected a pipe 123 which is connected to the casing 124 of valve chamber 125 and opens into said chamber. In this casing is the tubular valve 126 in 105 which is partially housed the spiral spring 127, one end of which bears against the casing of the valve chamber and the other end bears against the valve and normally holds said valve pushed partially out of said chamber. To the outer end of valve 126 is pivotally connected link bar 128 which is also pivotally connected to arm 129 on the shaft 130. Shaft 130 extends through the side bar 131, which bar forms a part of the frame 115 of the machine and said shaft is revolvable in said bar. On the other end of said shaft is an arm 132 (shown in Fig. 5) which when said shaft is rocked by the movement of said valve to the left causes said trap door 43 to 120 rise and form an integral part of track 44, so that when said trap door is in its elevated position said roller 42 will travel backwards and forwards without causing the form box 36 to rise so that the type therein cannot 125 engage roller 37. Whenever there is no paper in the paper carrier it will be seen that there is nothing to close ports 47 so that the action of piston 72 cannot exhaust the air from pipe 59 and consequently cannot ex- 130

haust the air from chamber 125, and that when chamber 125 is not exhausted the power of spring 27 is such that through connecting mechanism it keeps trap door 43 elevated and the form box remains in its depressed position, but when a sheet of paper is in the carrier it is sucked upon ports 47 so that chamber 46 and pipe 59 are exhausted, thereby also exhausting through pipe 123 chamber 125 when the power of spring 127 is overcome and arm 132 is withdrawn from supporting trap door 43 in its elevated position and said trap door will fall of its own weight. However, to insure the positive action of said trap door a spring 133 is provided to depress said trap door as shown in Fig. 5.

Having described my invention what I claim is:—

1. In a printing press, guideways; a reciprocating type carrying frame traveling on said guideways; a form box carried by said frame and vertically movable thereon; a reciprocating rotary impression cylinder; and means operable by exhaust to cause the movement of the form box toward and from said cylinder.
2. In a printing press, guideways; a reciprocating type carrying frame traveling on said guideways; a form box carried by said frame and vertically movable thereon; shafts mounted in bearings secured to said type carrying frame and having a portion thereof flattened, said form box being supported by said shafts; and mechanism operable by exhaust to rock said shafts.
3. In a printing press, a reciprocating feed box having the front end of the bottom

open said feed box being adapted for the reception of the paper to be printed; a support for said feed box; a reciprocating rotary impression cylinder having in its periphery an air chamber provided with ports in the periphery thereof; mechanism for exhausting the air from said air chamber when the front end of a sheet of paper in said feed box registers with said air chamber; means for releasing said exhaust upon the revolution of said cylinder; guideways; a reciprocating type carrying frame traveling on said guideways; a form box carried by said frame and vertically movable thereon; type in said box; and mechanism operable by exhaust to cause the movement of the form box to carry the type into engagement with the paper on said cylinder.

4. In a printing press, a reciprocating rotary impression cylinder having in its periphery an air chamber provided with ports in the periphery thereof; a control valve chamber; a connection from said air chamber to said control valve chamber; an exhaust pump; a connection therefrom to said control valve chamber; a valve in said control valve chamber; a cam in engagement with said valve; a connection from said cam to said pump; and mechanism to operate said cam.

In witness that I claim the foregoing I have hereunto subscribed my name this 29th day of December, 1906.
